UNITED STATES PATENT OFFICE.

PATRICK KANE, OF BRUNO, MINNESOTA.

LOADER.

1,301,706.

Specification of Letters Patent. Patented Apr. 22, 1919.

Application filed September 21, 1918. Serial No. 255,116.

To all whom it may concern:

Be it known that I, PATRICK KANE, a citizen of the United States, residing at Bruno, in the county of Pine and State of Minnesota, have invented new and useful Improvements in Loaders, of which the following is a specification.

This invention relates to loaders and it consists in the novel features hereinafter described and claimed.

An object of the invention is to provide a loader of simple and durable structure which may be conveniently used for loading ties upon railway cars or similar vehicles and for removing the ties from the cars or vehicle.

With this object in view the loader comprises masts which are positioned vertically upon the ground and spaced from each other. Cable tracks are trained over the upper ends of the masts and suitably secured at their ends. A cable is connected at its end portions with the masts and is located below the cable tracks. A traveler is mounted for movement along the cable tracks and a carriage is suspended from the traveler. An engine is mounted upon the carriage. Shafts are journaled upon the carriage and means are provided for rotating either of the last mentioned shafts from the shaft of the engine. One of the shafts which is journaled upon the carriage is provided with a drum around which the intermediate portion of the second mentioned cable is wound. A hoisting cable is arranged to wind upon the drum of the other shaft and the said hoisting cable may be trained around the pulleys of suitable blocks one of which is attached to the carriage and the other block may sustain the weight of the load.

In the accompanying drawing:

Figure 1 is a side elevation of the loader; Fig. 2 is a top plan view of the same; Fig. 3 is a bottom plan view, and Fig. 4 is a longitudinal sectional view.

The loader comprises masts 1 which are positioned vertically upon the surface of the ground. Track cables 2 are trained over the upper ends of the masts 1 and the said cables are extended parallel with relation to each other. A cable 3 is connected at its ends with the masts 1. A traveler 4 is arranged for movement along the cables

3. A carriage 5 is supported from the traveler 4 by means of hangers 6 which may 55 be in the form of rods or other suitable structure.

An engine is mounted upon the carriage 5 and its shaft 7 is provided in the vicinity of one end with a fly wheel or pulley 8. A 60 friction pulley 9 is mounted upon the shaft 7 and the said pulley may be composed of paper or any other suitable material. A shift lever 10 is pivoted upon the carriage 1 and may be moved to shift the pulley 9 65 laterally. A propelling shaft 12 is journaled upon the carriage 5 and is provided at a point between its ends with a drum 13. The drum 13 is provided with a concaved periphery. A disk 14 is mounted upon the 70 shaft 12 and is located opposite a friction pulley 9.

A hoisting shaft 15 is journaled for rotation upon the carriage 5 and a drum 16 is mounted upon the intermediate portion 75 of the hoisting shaft 15. A disk 17 is mounted upon the shaft 15 and is located opposite the friction pulley 9.

A cable 18 is arranged to wind upon the drum 13 and the intermediate portion of 80 the said cable is trained around the pulley of a block 19 to which the load, to be lifted, is attached. A block 20 is carried by the carriage 5 and the intermediate portion of the cable 18 is trained around the pulley of 85 the block 20. The other end of the cable 18 is attached to the block 19 as best shown in Fig. 1 of the drawing. Brake levers 21 are pivoted upon the carriage 5 and the said levers carry at their undersides shoes 22 90 which may be brought into frictional contact with the peripheries of the pulleys 14 and 17. Rack bars 23 are mounted upon the carriage adjacent the free ends of the levers 21 and the levers may be provided 95 with pawls for engaging the said rack bars whereby the said levers will be held at adjusted positions.

It is apparent that when the shaft 15 is held at a state of rest by the application of 100 the brake shoe to the periphery of the disk 17 and the shaft 12 is rotated from the shaft 7 when the disk 9 is in contact with the disk 14 the carriage 5 and traveler 4 will move along the cable track 2 inasmuch as 105 the intermediate portion of the cable 3 is

wound about the drum 13. In view of the fact that the drum 13 is provided with a concaved periphery the coil in the cable 13 will be held approximately midway between 5 the ends of the drum 13.

When the carriage 5 has moved to a desired point along the cable tracks the lever 10 is swung whereby the disk 9 is moved out of engagement with the disk 14 and 10 the shaft 2 is held against rotation by the application of the shoe 12 carried by the lever 21 to the periphery of the disk 14. When the disk 9 is moved into engagement 15 with the disk 17 the shaft 15 is rotated whereby the cable 18 is wound upon the disk 16 and consequently any load which is attached to the block 19 may be raised or lowered according to the direction in which the shaft 15 rotates.

20 From the foregoing description taken in conjunction with the accompanying drawing it will be seen that a loader of simple and durable structure is provided and that the same may be used to advantage for load-

ing material upon railway cars or for re- 25 moving material therefrom.

Having described the invention what is claimed is:—

In a loading apparatus, a carriage, an engine mounted on said carriage, a friction 30 pulley on the shaft of said engine, a pair of shafts journaled in said carriage at the sides of and in spaced parallel relation to said engine shaft, friction pulleys on said second 35 named shafts in position to be engaged selectively by said first named friction pulley, means for shifting said first named pulley into engagement with either of said second named pulleys, a block supported above said first named pulley, levers pivoted upon said 40 block, brake shoes on said levers engageable with said second named pulleys and means for holding said levers in selected positions for controlling or preventing rotation of said drums. 45

In testimony whereof I affix my signature.

PATRICK KANE.
